UNITED STATES PATENT OFFICE.

ELMER E. WHITE, OF CATO, NEW YORK.

KODAK-CASE.

1,260,737.

Specification of Letters Patent. Patented Mar. 26, 1918.

Application filed October 21, 1916. Serial No. 126,958.

To all whom it may concern:

Be it known that I, ELMER E. WHITE, a citizen of the United States, residing at Cato, in the county of Cayuga and State of New York, have invented certain new and useful Improvements in Kodak-Cases, of which the following is a specification.

This invention relates to camera cases.

One of the main objects of the invention 10 is to provide a camera case of neat appearance and durable construction so constructed as to be moisture proof and to exclude all dust or grit from the interior of the case. A further object is to provide a case of 15 simple construction which is adapted to hold a camera and an extra roll of films. A still further object is to provide a very durable case of simple construction and operation which can be produced at relatively low 20 cost. Further objects will appear from the detailed description.

In the drawings:

Figure 1 is a front view of the case in closed position,

25 Fig. 2 is a side view of the same, the carrying strap being omitted for the sake of clearness,

Fig. 3 is a section on line 3—3 of Fig. 1, Fig. 4 is a vertical longitudinal center 30 view taken through the case substantially on line 4—4 of Fig. 3,

Fig. 5 is a section on line 5—5 of Fig. 1, and

35 Fig. 6 is a detailed sectional view taken through the lock casing.

My case is composed of two telescopically connected sections. The lower section 1 is formed from sheet aluminum, or other suitable non corrodible material. The lower 40 end 1^a of section 1 is of approximately semi-circular shape in cross section and is provided with a concaved felt pad 2 which is adapted to support a camera within section 1. The upper section 3 is of somewhat 45 greater cross area than lower section 1 and extends a considerable distance downward about the upper portion thereof. This upper section 3 is provided, at its lower edge, with an integral peripheral flange 4 which 50 fits snugly about section 1. Above this flange, on the inner face of each wall 3^a of section 3, is secured a packing member. This member is formed from a tubular strip 5 of leather which is riveted, or otherwise secured, to the inner face of side walls 3^a 55 intermediate its edges so as to provide the upper elliptical member 5^a and the lower elliptical member 5^b. The lower member 5^b is provided with a filling 6 of felt, cork, or other suitable material. The upper member 5^a and the lower member 5^b have their inner faces in substantial vertical alinement 60 and are adapted, when the upper section 3 is placed over the lower section 1, to fit snugly about the lower section so as to provide a fluid-tight double closure therewith. 65

In the upper end portion of upper section 3 is secured a film receiving casing. This casing is formed of suitable blocks 7 which are secured together at their corners by double tongue and groove joints, and are firmly secured in section 3. These blocks form a rectangular chamber 8 which is adapted to receive a box containing a roll of films. Chamber 8 is closed by means of a door or 70 closure member 9 which is hingedly secured to the end block 10 as at 11. This door is provided with a recess on which is slidably mounted a securing bolt 13 the end of which 75 engages into a latch plate 14 secured to the under face of the end bar 15. By moving this bolt out of engagement with the latch plate the door 9 may be swung outward and downward about its pivotal axis so as to permit the roll of films to be removed 80 from the film chamber 8.

A packing ring or gasket 16 of soft rubber is secured to the underface of the film 85 casing and is adapted, when the case is in closed position, to engage the upper edge of the lower section 1 so as to effect a liquid 90 tight closure therewith. By means of the packing members 5^a and 5^b at the lower end of the upper section, and the gasket 16 interposed between the upper end of the lower 95 section and the inner face of the film casing, I insure that no moisture or dust, or the like, can enter the casing. In addition, I provide a separate compartment for an extra roll of films which is effectually protected from moisture or dust, or the like. 100 The upper section 3, like the lower section 1, is constructed of sheet aluminum. This provides a light casing which is very strong and durable, and is of neat appearance.

105 A plate 17 is secured to the front of the lower section 1 of the casing and carries a casing or housing 18. Mounted in this cas-

ing is a bell crank 19 which is pivoted at 20. The upper end of the vertical arm of this bell crank is turned over to provide an integral hook 21. This hook is adapted to 5 engage over a head 22 which extends downwardly from a plate 23 secured to the upper section 3. A tension coil spring 24 has one end secured to the vertical arm of bell crank 19 above its pivotal axis, and the other end 10 secured to the plate 17. This spring acts to normally hold the vertical arm of the bell crank in operative position to be engaged by head 22 so that when the upper section of the casing is moved into its lowermost position, the hook 21 engages over the head 15 so as to secure these two sections together. The lower arm 19^a of the bell crank extends through a slot 18^a through one side of the housing and is rounded to provide a finger 20 grip 25 by means of which the upper section may be released for opening the casing. The inward movement of the vertical arm of the bell crank is positively limited by a pin 26 positioned to engage the horizontal 25 arm 19^a thus insuring that hook 21 will, at all times, be in proper position to engage over the head 22 when the casing is in closed position.

For carrying the case, each of the sections 30 1 and 3 is provided, at each side, with a plurality of strap guides 27 secured thereto. These guides are adapted to receive a strap 28 which passes about the sides of the casing and beneath the casing so as to support the same in the usual manner. When 35 it is desired to open the casing, the bell crank 19 is operated so as to release head 22, after which the upper section 3 may be moved outward along the strap 28.

40 In using my case, the camera is placed within the lower section 1 which is made the proper size for this purpose, and rests on the pad 2. The extra roll of films is placed within the film casing so as to be 45 readily accessible. Of course, it will be evident that, by varying the dimensions of the casing it may be adapted for use in connec-

tion with cameras of various sizes or for other similar purposes.

There may be slight changes made in the 50 construction and arrangement of the different parts of my invention without departing from the field and scope of the same, and I intend to include all such changes, as fall within the scope of the appended claims, in 55 this application in which a preferred form only of my invention is disclosed.

What I claim is:

1. In a casing of the character described, the combination of a lower section, an upper section adapted to fit snugly about the lower section and to extend downward about the same, means carried by the upper section for effecting a fluid tight closure between the upper section adjacent its lower end and the lower section, a film casing carried by the upper section, means for closing the inner end of the film casing, and a packing member interposed between the upper end of the lower section and the film casing for effecting a fluid tight closure about the upper end of the lower section. 60

2. A casing of the character described having a lower section, an upper section fitting snugly about the upper portion of the lower section, a film casing carried by the upper section, a door hingedly secured to the underside of the film casing for closing the same, packing members carried by the upper section adjacent its lower end adapted to 80 effect a fluid tight closure between the same and the lower section, and a packing member concentric with said door interposed between the film casing and the upper end of the lower section for effecting a fluid tight 85 closure between the said casing and lower section. 75

In testimony whereof I affix my signature in presence of two witnesses.

ELMER E. WHITE.
